UNITED STATES PATENT OFFICE

RUDOLF FUCHS, OF EGGENBERG, NEAR GRAZ, AUSTRIA

SHOE NAIL FOR MOUNTAIN SHOES

Application filed February 9, 1931, Serial No. 514,666, and in Austria January 27, 1930.

The invention relates to shoe nails for mountain shoes.

The object of the invention is to provide a shoe nail for mountain shoes, which may be easily attached without the use of special tools in a manner to withstand all stresses during actual use without becoming loose. The nail according to the invention provides a sharp walking edge at the outermost circumference of the sole, thus ensuring surefooted walking on steep slopes or snow-fields.

The nail according to the invention is especially designed for heavy mountain shoes with laminated soles held together and united with the upper part of the shoe by a hand-stitching and is so designed as not to damage these stitches when inserted, to protect the same against wear and to hold the leather-sheets of the sole together.

20 Shoe nails for mountain shoes are already known which are provided with straight projections which, when in use, will, however, become loose as straight projections or prongs may easily be pulled out of the sole; they 25 have moreover the drawback that great care must be used when the projections of the side plates, are bent down and driven into the upper edge of the sole, and it is necessary to use special tools to avoid cutting the thread of the 30 stitching which is not protected at this point.

The shoe nail according to this invention avoids this drawback by virtue of its novel design, which renders it possible to insert it from above without any danger of damaging 35 the stitching and without the use of any tool other than a hammer and to obtain a solid anchorage, so that the nail will not become loose when used. Another advantage of the shoe nail according to this invention is that it may 40 be manufactured at very low cost of a single piece of sheet-metal without hand-forging.

The shoe nail according to the invention comprises a side-plate with two long projections on one end and a heavy ground engaging projection at the other end. Rigidly secured at right angles to said edge of the side-plate is a bottom-plate and flexibly joined to said ground-engaging projection are hook-shaped claws preferably arranged at both 50 sides of the bottom plate. The prongs of

these claws which are to be inserted into the sole are curved with the center of curvature at the flexible joint, in order to obtain a sure anchor hold of the nail.

In another modification of the invention 55 the bottom plate and the claws are integral with each other and both are flexibly joined to the ground-engaging projection.

Fig. 1 shows a shoe nail according to the invention by an elevation;

Fig. 2 by a side view and

Fig. 3 by a plan view.

Fig. 4 shows the nail when being driven into a shoe sole in a position according to the side view of Fig. 2,

Fig. 5 shows the same after the part of the nail projecting from the sole in Fig. 4 has been bent downward and

Fig. 6 a nail completely inserted into the sole.

Fig. 7 shows the nail driven and inserted into the sole with the latter in a perspective view.

Fig. 8 shows another modification of the nail according to the invention.

Referring to Figs. 1 to 3, 1 designates the working or ground-engaging projection of the nail. 3 is the side-plate with long projections 2. 4 is the bottom plate which may have a hole 6 for the insertion of a screw or tack. The claws 5 are flexibly joined at 7 to the side-plate and have prongs 5a of arcuate form, the center of curvatures of the prongs 5a being at 7. To attach the nail to the shoe, the projections 2 are driven from above into the upper protruding edge of the sole 8, as shown in Fig. 4. Then the side-plates are bent downward until they rest flat against the sides of the sole and the bottom plate lies smoothly against the underside of the sole 8. (Fig. 5). In this position, the points of the prongs 5a are just touching the sole. If they are now driven into the same (Fig. 6) they move along an arcuate path around the flexible joint 7 and due to their arcuate shape they can easily enter into the leather and will hold firmly. If desired, a screw or tack may be inserted through the hole 6 though this is not necessary in most cases. As shown in Figs. 6 and 7, the stitching 9 is not damaged by this 100

operation and will be effectively protected against wear, as shown in Fig. 7.

In the modification shown in Fig. 8, the claws 5 and the bottom plate are formed of a single piece. The arcuate form of the prongs 5a is clearly visible.

What I claim is:—

1. In an article of the class described, a side-plate provided at one end with projections adapted to be inserted into the upper protruding edge of the sole of a shoe from above and having a rigid ground engaging projection at the other end, a bottom plate rigidly secured at right angles to said ground-engaging projection and hook-shaped claws joined to said projection and flexible along the line of joining, said claws having prongs adapted to be driven into the sole, and said prongs being of arcuate form with the center of curvature at the line of joining of the claws to the ground engaging projection.
2. In an article of the class described, a side-plate provided at one end with projections adapted to be inserted into the upper protruding edge of the sole of a shoe from above and formed at its other end with a thickened portion constituting a ground engaging projection, a bottom plate joined to said plate at an angle adjacent the ground engaging projection, said claws being flexible along a line adjacent said plate, said claws having prongs to be driven into the shoe sole, and said prongs being of arcuate form with the center of curvature at the flexible line of the claws.

In testimony that I claim the foregoing as my invention, I have signed my name.

RUDOLF FUCHS.
